NEW JERSEY, ASSIGNEES TO UNITED FILTERS CORPORATION, OF BROOKLYN, NEW
YORK, A CORPORATION OF DELAWARE.

FILTER-CASING.

1,337,733.

Specification of Letters Patent. Patented Apr. 20, 1920.

Application filed June 19, 1918. Serial No. 240,877.

To all whom it may concern:

Be it known that we, ERNEST J. SWEETLAND, a citizen of the United States, residing in Montclair, county of Essex, and State 5 of New Jersey, and CARROLL M. STANLEY, a citizen of the United States, residing in Newark, county of Essex, and State of New Jersey, have invented certain new and useful Improvements in Filter-Casings, of 10. which the following is a specification.

The present invention relates to certain new and useful improvements in pressure filter casings which comprise two complementary sections hingedly connected at one 15 side thereof for opening and closing the casing, packing means being provided at the meeting edges of the sections to insure a liquid tight joint therebetween, one object of the invention being to provide novel 20 means whereby the meeting edges of the hinged side of the casing sections can be positively adjusted relatively to each other to maintain a liquid tight joint and to take up wear of the parts and packing.

25 A further object of the invention is to provide novel means whereby the degree of adjustment may be varied at different points along the hinged side of the casing so as to compensate for irregularities due to the casting 30 of the casing sections, and to cause different pressures to be exerted in the packing at various points in the length of the casing as may be necessary to maintain a liquid tight joint.

35 Another object of the invention is to provide a novel construction of hinge specifically adapted for use with fluid tight casings formed in sections or having a hinged cover, whereby the hinge may be adjusted 40 relatively to the casing sections which it connects so as to correct inaccuracies in the swinging relations of the parts which are due to improper hinge mounting.

45 For a full understanding of the invention reference is to be had to the following description and accompanying drawings in which:

50 Figure 1 is a side elevation of the hinged side of a sectional pressure filter casing showing one embodiment of the present invention.

Fig. 2 is an enlarged fragmentary trans-

verse vertical sectional view through the hinged side of the casing, showing one of the hinge members in side elevation.

55

Fig. 3 is a front elevation of the same.

Fig. 4 is a top plan view thereof.

Corresponding and like parts are referred to in the following description and indicated in all the views of the drawing by the same 60 reference characters.

For the purpose of illustration, the invention is shown in connection with a conventional type of pressure filter casing, although it is to be understood that the invention is 65 susceptible of use in connection with vacuum filters or practically all openable containers.

Specifically describing the present embodiment of the invention the numeral 1 designates the upper section, and 2 the lower section of a pressure filter casing A, which is of the type of casing comprising two complementary sections hingedly connected at one side and secured together at the other side by suitable fastening means. One side 75 of the upper section 1 of the casing is provided with a plurality of laterally projecting hinge lugs 3 which are spaced apart longitudinally of the casing and are provided with vertically disposed bores 4. The corresponding side of the lower section 2 of the casing is provided with an equal number of similarly formed hinge lugs 5, which are provided with vertical bores 6 and are adapted to coöperate with the lugs 3 of the 80 upper casing to receive hinge members B, which serve to hingedly connect the two sections 1 and 2. The lugs 3 and 5 are spaced from the meeting edges of the casing sections 1 and 2 to provide clearance for the 85 hinge members B, and the lower face of each of the lugs 3 is undercut at 3^a to provide a vertical flat shoulder 3^b. A liquid tight joint is maintained between the meeting edges of the sections 1 and 2 by a packing 90 strip 7 carried by one section and snugly engaging the other when the casing sections are moving together.

Each hinge member B comprises an eye bolt 8 having the eye 8^a and threaded bolt 8^b 100 which is adapted to be loosely received in the vertical bore 6 of the lug 5 of the lower casing section 2. A castle nut 9 is threaded on the end of the bolt 8^b and engages the

- underside of the lug 5, a cotter pin 10 being provided for engaging openings 8^c in the bolt and coöperating with the notches of the castle nut to hold the nut on the said bolt.
- 5 A hinge bolt 11 is adapted to be loosely fitted in the vertical bore 4 of the lug 3 of the upper section 1 of the casing, said bolt being provided at its lower end with an enlarged bifurcated head 11^b, the arms of
- 10 which are provided with transverse openings 11^c and straddle the eye 8^a of the eye bolt 8 fitted in the corresponding lug 5 of the lower section 2, a hinge, pintle 12 being inserted through the openings 11^c and eye
- 15 8^a to connect the hinge bolts 8 and 11. The upper end of the bolt 11 is threaded and receives an adjusting nut 13, which engages the upper side of the lug 3, and a lock or jam nut 14.
- 20 With this construction it will be seen that the tightening or loosening of either the adjusting nut 13 or castle nut 9 of any of the hinge members B will cause the sections 1 and 2 of the casing to be drawn together or
- 25 separated so as to cause greater or less pressure on the packing strip 7 as may be desired. Further it will be noted that each hinge member B is independently adjustable so that the relation of the two sections
- 30 1 and 2 at practically any point in the length thereof can be varied to compensate for irregularities in the sections or to adjust improper hanging of the sections on the hinge members. Should the sections become
- 35 warped, it will be obvious that by proper tightening of some of the hinges and loosening of others the defect can be easily overcome. With reference to Fig. 3 of the drawing it will be noted that the enlarged head
- 40 11^b of the hinge bolt 11 engages the flat shoulder 3^b so that the hinge bolts are prevented from turning while the nuts are being adjusted.
- 45 It is an important feature that the invention provides means for adjusting the hinged side of the sections of a pressure filter casing or other openable fluid pressure container so as to always maintain a liquid tight joint between the sections. Further,
- 50 the provision of a plurality of independently adjustable hinges allows varied adjustments of the casing sections at different points in their lengths which in many instances will overcome the necessity of special work for providing proper fitting surfaces to the casing sections or special packing.
- 55 Having thus described our invention what we claim as new and desire to secure by Letters Patent is;
- 60 1. In a hollow casing, the combination with two complemental casing members which are provided with meeting edge portions and having thereat corresponding
- 65 openings, hinge bolts extending loosely
- through the openings, a hinge pintle connecting the inner ends of the said bolts, and means for locking both of the hinge bolts in an adjusted position within the respective openings for adjusting and maintaining the hinge pintle in the plane of said meeting edge portions of the casing members.
2. In a hollow casing, the combination with two complemental casing members each of which is provided with a lug having an opening therein and spaced from the meeting face of the member, threaded hinge bolts extending loosely through the openings of the lugs, a hinge pintle connecting the inner ends of the bolts, and adjusting nuts threaded upon the outer ends of the bolts and engaging the rear faces of the lugs to hold both of the bolts in an adjusted position to admit adjustment of the hinge pintle relatively to each casing member.
3. In a hollow casing, the combination with two complemental casing members each of which is provided at an edge portion thereof with an outstanding lug which has an opening therein and is spaced from the meeting face of the member, the inner end of one of the lugs being formed with a shoulder, threaded hinge bolts extending loosely through the openings of the lugs and terminating at their inner ends in heads, one of which engages the before mentioned shoulder to lock the corresponding bolt against rotation, a hinge pintle connecting the heads at the inner ends of the bolts, and nuts threaded upon the outer ends of the bolts and engaging the outer faces of the lugs to hold both of the bolts in an adjusted position and permit adjustment of the hinge pintle relatively to each of said casing members.
4. In a hollow casing, the combination with two complemental elongated casing members, packing between the meeting edges of the members, a plurality of independent hinge members connecting the complemental members at intervals along one of the longitudinal edges thereof, and means for independently adjusting the several hinge members to obtain a tight joint between the complemental casing members throughout the entire area of the meeting faces thereof.
5. In a hollow casing, the combination with two complemental elongated casing members provided at one of the long sides thereof with a series of corresponding outstanding lugs having openings therein, packing between the meeting faces of the complemental members, hinge bolts extending loosely through the openings of the lugs, hinge pintles connecting the inner ends of each pair of hinge bolts, and means for holding the hinge bolts in adjusted positions within the openings of the lugs, each set of hinge bolts being independently adjustable on each casing member so as to obtain an

even bearing upon the packing throughout the entire area of the meeting faces of the complementary casing members.

6. In a hollow casing, the combination with two casing members each having an outwardly projecting lug provided with an opening therein, of a hinge comprising a threaded eye bolt adapted to be fitted loosely in the opening of one of the lugs and pro-

vided with a nut engaging the said lug, a 10 threaded hinge bolt fitted loosely within the opening in the other lug and provided with a nut engaging said lug, and a hinge pintle pivotally connecting said eye bolt and hinge bolt.
